WET MUFFLER WITH CUP-SHAPED BAFFLES
Sergius Vernet, Yellow Springs, Ohio, assignor to Vernay
Laboratories, Inc., Yellow Springs, Ohio, a corporation
of Ohio

Filed Oct. 29, 1963, Ser. No. 321,386
3 Claims. (Cl. 181—52)

This invention resides in the provision of a wet muffler suitable for use with internal combustion engines, and more particularly with those engines that involve the introduction of water into their exhaust systems.

Attempts have been made in the past to provide mufflers with baffles so as to effect a mixing of gases and water in an effort to reduce noise, lower temperatures and also to reduce back pressure. These mufflers and their baffles have taken many different forms. Typical examples of these older arrangements may be found in the United States patents to Bourne 1,821,688; Hoffar 2,877,860 and Betts 3,077,240. These prior arrangements, however, have achieved only limited success.

A very important object of this invention, therefore, is to provide a muffler incorporating a regulating means which will effect a reduction in engine noise condition to a much greater extent than has so far been accomplished by devices heretofore known in the art.

It is also an important object of this invention to provide a muffler regulating means which lowers the temperature of the escaping gases from the engine system and which also reduces back pressure, all to a much greater extent than has been accomplished to date by prior art arrangements.

A further important object of this invention is to provide a muffler regulating means which will effect a substantial reduction in the noxious and objectionable gas odors emitted from the engine through its exhaust system.

It is also an object of this invention to provide a muffler which readily lends itself to manufacture from a wider range of materials than has heretofore been economically feasible.

A further object of the invention is to provide a muffler which is simple to construct and which is durable in use.

These and other objects and advantages of this invention will become apparent to the person skilled in the art from the description to follow, keeping the foregoing remarks and objects in mind, and with reference to the accompanying drawings, in which drawings like numerals are employed to designate like parts throughout, and in which

FIG. 1 is a longitudinal section of a muffler and regulating means constructed according to the teachings of this invention and shown diagrammatically as applied to an engine exhaust system which incorporates a water supply therein.

FIG. 2 is a section taken on the line 2—2 of FIG. 1,

FIG. 3 is a longitudinal section of a modification of the invention,

FIG. 4 is a section taken on the line 4—4 of FIG. 3,

FIG. 5 is a longitudinal section of another modification of the invention,

FIG. 6 is a section taken on the line 6—6 of FIG. 5,

FIG. 7 is a section similar to that of FIG. 2 but showing yet another modification of the invention, and

FIG. 8 is a perspective view of a modified baffle which may be used as a part of this invention.

The objects of this invention are achieved by a unique utilization of the water content of the total exhaust throughput. This in turn is accompanied by virtue of the relative location of the regulating means in the muffler body, the distinctive shape of the baffle-like regulating means, the location and configuration of openings in the

2

baffle-like regulating means, and the utilization of the muffler body configuration itself as an active agent in the total muffling function.

A principal feature of this invention resides in providing the muffler body with baffle-like regulating means which have an opening or openings, for the passage of gas and water therethrough, the cross sectional area of which openings will be substantially less than the cross sectional area of the inlet by which such gas and water enter the muffler body. This arrangement and relationship of internal baffle opening to muffler inlet serves to force the water and exhaust gases through the baffle opening at a higher velocity than exists at the muffler inlet. This in turn maximizes the co-mingling of the water and gases as they pass through the baffle openings. In the preferred arrangement of this invention only a single baffle is used, and this in large measure makes possible this area relationship between the baffle opening, or openings, and the inlet opening. By way of example, if the area of inlet opening is three square inches, the aggregate of the areas of the openings in such baffle should be in the range of two square inches.

The muffler comprises a hollow body having an inlet which is connected to the exhaust system of an engine and an outlet through which the gases and water are finally discharged. The regulating means is located between the inlet and outlet and is so formed and positioned as to bring about an extremely efficient commingling of the water and gas within the muffler body. Preferably the baffle-like regulating means has a basic cup configuration which, together with the hollow muffler body itself, provides a maximum volumetric space for the unhampered expansion of the hot exhaust gases. At the same time the total arrangement is such as to permit maximum development of water intrusion into and across the area of the outlet whereby to direct a curtain of water across such outlet.

Referring now to FIGS. 1 and 2, one embodiment of the invention will be described. The hollow muffler body, preferably but not necessarily cylindrical in form, is depicted as constructed of two members 10 and 11. In this particular arrangement the section 10 is provided with an inlet 12 and the section 11 is provided with an outlet 13. The inlet 12 is shown engaged with a header pipe or exhaust system generally indicated at 14. As diagrammatically illustrated by the arrow 15, it will be understood that both water and exhaust gases will flow through this system into the muffler. Whatever the precise arrangement, it is to be understood that a combination of gases and water will enter the muffler via the inlet 12.

The baffle-like regulating means having a generally cup-shaped configuration is generally indicated at 16. This member has an annular flange 17. In the embodiment of FIGS. 1 and 2 this flange 17 is cut away as indicated at 18 in order to provide an opening or passageway 18 for water and gas, as will be described more fully shortly. The cross sectional area of this opening 18 should be substantially less than that of inlet 12.

Preferably the elements 10, 11 and 16 are assembled as follows. The member 11 is formed with an outwardly stepped annular portion 19 arranged so as to form the annular shoulder 20. The parts are so dimensioned that the annular flange 17 (except where it is cut away as indicated at 18) will abut the shoulder 20 and the member 10 will be just nicely received by the enlarged portion 19 of the member 11; the member 10 will also bear against the flange 17 thus holding such flange firmly against the shoulder 20. All of the members 10, 11 and 16 may be molded of polyester resin and fiberglass in which case the members 10 and 11 are secured together by the application of an appropriate adhesive over the

full surface area of those portions of these two sections 10 and 11 that will contact one another when assembled. In alternative constructions wherein the sections are made of metal, the joint may be sealed against gas leakage by an appropriate sealant or gasket and held in assembly by welding, or other suitable means of attachment.

Although the cup-shaped regulating means of baffle 16 is preferred, it has been determined that a disc type baffle such as shown at 30 in FIGURE 8 will suffice. Again, the cross sectional area of the opening (or openings) 30a in this baffle must be less than the cross sectional area of the inlet opening at 12.

It should be noted that the muffler of FIGS. 1 and 2 is composed of just three basic elements, namely, the upstream section 10, the downstream section 11 and the regulating means 16. As indicated, the cup-like regulating means 16 is inserted, protruding end first, into the upstream end of the section 11 so that its flange 17 will engage the shoulder 20; this flange also has a snug fit within the enlarged portion 19 of the section 11. The section 10, which also has a snug fit within the portion 19 of the member 11, is then pressed home against the flange 17 to effect, in addition to the lock secured by the adhesive aforementioned, a secure mechanical lock of the regulating means 16 between the downstream end of the section 10 and the shoulder 20 of the upstream end of the section 11.

In one form of the invention there is a particular relationship between the regulating means 16 and downstream casing section 11. The exterior surface of the member 16 parallels, throughout its major extent, the interior surface of the section 11 so as to provide a uniform circumferential channel 21 between the members 16 and 11. This channel 21 extends from adjacent the flange 17 to approximately the beginning of the curved neck portion 22 leading to the discharge or outlet 13. The importance of this substantially uniform circumferential channel 21 will be made clear as the description proceeds.

As has been earlier noted, the flange 17 is cut away as indicated at 18. In engine operations involving the use of this muffler, at low or idle speeds the volume of water retained by the muffler is at a level approximately that of the lower limit of the outlet 13 in which instance the opening 18 in the lower portion of the flange 17 is usually almost entirely obstructed by water; preferably the opening 18 is of such size that at least some small portion thereof will not be obstructed by water in this condition whereby gases may escape through such unobstructed portions to the outlet 13. With increase in engine speed, and therefore increase in throughput of exhaust gases and water within the muffler, the level of retained water in the muffler is forced lower and lower, thereby exposing to the muffler atmosphere more and more of the cross-sectional area of the flange opening 18, thus effecting a most advantageous balance between noise reduction and minimization of back pressure. With the construction shown and described, such reaction is fully automatic and self-adjusting. And all of this is accomplished with a muffler composed of just the three basic elements 10, 11 and 16, arranged and configured as shown and described.

In the preferred arrangement of this invention the regulating means 16 will be cup-shaped as shown and so disposed with respect to the inlet 12 as to form the expansion chamber 24. And the channel areas 21 have been found desirable; these areas 21 will further the venturi effect achieved through the baffle opening 18. The more important features of this invention, however, are the relationship of the baffle opening area to the input opening area, and a configuration which permits the exposure of more and more of the baffle opening with increases in engine speed and exhaust water and gas throughput.

Referring now to FIG. 7, a modification of the invention is illustrated. In this modification the only change,

as compared with the embodiment of FIGS. 1 and 2, has been to provide the flange 17 of the regulating means 16 with an additional opening 23 located substantially at the top of the muffler when in use. As earlier noted it is possible, when the engine is operating at low or idle speeds, that the volume of water retained by the muffler will either entirely, or almost entirely, obstruct the escape of gases through the lower opening 18. The upper opening 23, however, will be above any possible retained water level in the muffler during periods of non-operation, or slow operation, and will thus always provide a means of escape for the exhaust gases during these times, and upon starting, even if the retained water should actually freeze during such period of non-operation.

The operation of the embodiment of this invention shown in FIGS. 1 and 2, and in FIG. 7, will be further described as follows. As earlier noted, when the engine is operating at low speeds, all or a major portion of the flange opening 18 may be covered by retained water within the muffler body, at which time back pressures may build up. These back pressures may be minimized either by constructing the opening 18 so that some portion at least thereof will not be obstructed by retained water or by utilizing an additional opening such as that indicated at 23 in FIG. 7. With an increase in engine speed more and more of the water is forced out of the expansion chamber, which chamber is generally indicated at 24 and which may be considered as comprised of the area defined by the interiors of the upstream section 10 and regulating means 16, through flange opening 18 and, after being confined within but diffused circumferentially around, the exterior wall of the regulating means 16 and the interior wall of the casing section 11 in the circumferential channel 21, is impelled against the curved neck section 22 whereby it is deflected up into and mixed with the exhaust gases at the upstream end of the discharge opening or outlet 13, thereby effectively reducing the noise and washing the gases to eliminate the noxious odors.

As the engine speed is further increased there is a tendency to form a film of water around the interior surface of the casing section 10 by virtue of the centered position of the input opening for inlet 12 and the configuration of the curved neck portion 25, these two elements 12 and 25 in combination serving to direct the gaseous portions of the engine exhaust discharge down the center of the expansion chamber 24 while a portion of the water is forced outwardly and flows downstream along the chamber walls. With the opening 18 (and opening 23 where used) in the regulating means being located at the outer edge of such means, the tendency for the water portion of the gas-water through-put to be forced outwardly against the inner surface of the casing section 11 is continued and reinforced, this resulting in both casing sections 10 and 11 being substantially lined throughout their entire length with a film of water of varying thickness, which adds significantly to the total muffling effect.

Referring now to FIG. 3, a further embodiment of the invention is shown. In this arrangement the relative sizes of the basic muffler components 10, 11 and 16 have been changed to those indicated at 10a, 11a and 16a. It will immediately be apparent that the regulating means 16a has been considerably elongated. It is preferred that the components 10a, 11a and 16a will be assembled in the same manner as indicated in FIG. 1. There is still a large expansion chamber 24a which is defined by the interiors of the members 10a and 16a. At the same time, however, the length of the circumferential channel 21a has been considerably extended. The flange 17 of the regulating means 16a may be provided with openings in the same manner as indicated in FIGS. 2 and 7 or it may be arranged as shown in FIGS. 3 and 4. In these latter figures the flange 17 is provided with a plurality of openings 26. The basic operation of the arrangements shown in FIGS. 3 and 4 will be generally similar to those de-

scribed in connection with FIGS. 1, 2 and 7. Specifically, returning to FIG. 4, the arrangement is such that more and more of the openings 26 will be exposed to atmosphere with each incremental increase in engine speed and concomitant increase in volume of passed through water and gas with resultant lowering of the level of retained water within the muffler.

FIG. 5 depicts an embodiment of the invention which includes a plurality of regulating means, in this particular instance, two; more may be employed if desired. As shown, there will be the casing sections 10b and 11b along with the pair of regulating means 16b and an intermediate casing section 11c. These components may be assembled in the same manner as those illustrated in FIG. 1, as will be readily apparent to those skilled in the art.

The arrangement of FIG. 5 provides, in effect, two expansion chambers 24b and 27, and also a pair of substantially uniform circumferential channels 21b and 21c. These chambers and channels will operate and function in substantially the same manner as explained in connection with the embodiments of FIGS. 1 and 3.

The flange 17 of the regulating means 16b of FIG. 5 has been illustrated as provided with the opening 28 which is best seen in FIG. 6. The opening 28 is cut not only in the flange 17 but also into the body of the regulating means 16b. Again, however, the arrangement is such that at low or idle speeds at least some portion of the opening will be unobstructed by retained water within the muffler and, as engine speeds increase, more and more of the opening 28 will be unobstructed, that is, exposed to atmosphere, thus reducing back pressure in a manner similar to the embodiments previously described.

The various embodiments of this invention, as generally shown in FIG. 1, FIG. 3 and FIG. 5 will operate substantially the same, as fully described in connection with FIG. 1. It is believed, therefore, that a further description of the operation is unnecessary at this time. It should be pointed out, however, that the various types of flange openings illustrated in connection with the various regulating means 16 may be employed in any of the arrangements. Thus, for example, the regulating means 16 of FIG. 1 may utilize any of the flange openings depicted in FIG. 2, FIG. 7, FIG. 4 and FIG. 6; combinations of such openings may also be employed. Also, where applicable, these various types and arrangements of openings may be employed in the disc type baffle 30 of FIG. 8.

Thus, in the adaptation of the muffler of this invention to specific internal combustion engines, it is possible to combine any two or more of the various embodiments in different ways to best and most effectively bring about, for such specific internal combustion engines, maximum sound deadening with a minimum induced back pressure commensurate, for example, with the piston displacement, compression ratio, maximum r.p.m. and maximum g.p.m. of water and gas throughput of such engine. The basic elements, and their functions, however, will remain substantially as shown and described herein.

Also, in the muffler of this invention, the unit comprised of the three sections 10, 11 and 16 of FIGURE 1, for example, may be reversed so that what is normally the outlet 13 is attached to the exhaust system 14. This has the effect of reversing the flow of exhaust gases and water through the muffler. Although some of the advantages of the expansion chamber 24 may be lost in such arrangement, and possibly of the channel areas 21 also, nevertheless very good muffling effects will still be achieved. This is due to the importance of that arrangement wherein the cross sectional area of the baffle opening is substantially less than the cross sectional area of the inlet (now 13), which arrangement will still exist in this "reverse flow" form of the invention. And more and more of the baffle opening will still be exposed as engine speed increases, another important factor.

It will be further understood that while the invention has been shown as embodied in certain particular struc-

tures and arrangements, such structures and arrangements are not to constitute a precise limitation of the invention except insofar as they are specifically included in the subjoined claims. In this connection it will be apparent to those skilled in the art that modifications may be made in this muffler arrangement without departing from the scope and spirit of the claims which now follow.

I claim:

1. A wet muffler for attachment to an engine exhaust system which emits water and gas, said muffler comprising a hollow body having an inlet and an outlet, a cup-shaped regulating means located in said body between said inlet and said outlet, one portion of said body and the interior of said cup-shaped regulating means coacting to define an unobstructed expansion chamber in the region of said inlet, and another portion of said body and the exterior of said cup-shaped regulating means coacting to define a substantially uniform circumferential channel in the region of said outlet, said cup-shaped regulating means having at least one opening therein through which water and gas may pass in moving from said inlet to said outlet, and said cup-shaped regulating means having an outwardly extending annular flange at its open end, said opening being located in said flange.

2. A wet muffler for attachment to an engine exhaust system which emits water and gas, said muffler comprising a hollow body having an inlet and an outlet, a cup-shaped regulating means located in said body between said inlet and said outlet, one portion of said body and the interior of said cup-shaped regulating means coacting to define an unobstructed expansion chamber in the region of said inlet, and another portion of said body and the exterior of said cup-shaped regulating means coacting to define a substantially uniform circumferential channel

30 in the region of said outlet, said cup-shaped regulating means having at least one opening therein through which water and gas may pass in moving from said inlet to said outlet, said hollow body being comprised of two sections, one section having a telescopic fit with the other, and said cup-shaped regulating means having an outwardly extending annular flange at its open end, said opening being located in said flange, and said flange being positioned between said two sections.

3. A wet muffler for attachment to an engine exhaust system which emits water and gas, said muffler comprising a hollow body having an inlet and an outlet, at least one cup-shaped regulating means located in said body between said inlet and said outlet, one portion of said body and the interior of a said cup-shaped regulating means coacting to define an unobstructed expansion chamber in the region of said inlet, and another portion of said body and the exterior of a said cup-shaped regulating means coacting to define a substantially uniform circumferential channel in the region of said outlet, each of said cup-shaped regulating means having at least one opening therein through which water and gas may pass in moving from said inlet to said outlet, said hollow body being comprised of a plurality of sections, one section having a telescopic fit with another, and each of said cup-shaped regulating means having an outwardly extending annular flange at its open end, there being at least one said opening located in each said flange, and each said flange being positioned between two of said telescopic fitting sections.
